1

The invention relates to a cylindrical combination lock and in particular to a lock of the kind having pushers which are movable longitudinally in a revoluble cylinder and are displaceable against spring action by bits of adjustable length provided on a key to be inserted in the lock. The pushers are capable of being coupled with combination members which are displaceable longitudinally in a fixed part of the lock and are hereinafter termed tumblers, in order to bring them into a position corresponding to the combination of the key and they may be disconnected from those tumblers by a rotation of the above-mentioned cylinder in order to block this cylinder by placing themselves between said tumblers during the withdrawal of the key.

In a known cylindrical lock of this kind the above-mentioned pushers are each provided with two coupling members which are integral with lateral projections which are guided in longitudinal slots cut out in the revoluble cylinder. For the purpose of coupling, these members are adapted to engage in corresponding notches provided in each of said tumblers. This construction and arrangement of said parts of the lock has the disadvantage that the combination with which the lock has been locked may be detected by feeling the tumblers by means of a tool inserted through the hole of the lock or by means of the pusher itself.

An object of the invention is to obviate this disadvantage and to ensure the position of the tumblers of the lock being perfectly safe against detection by touch, by giving the lock a conformation such that on the one hand no insertion of a tool across said longitudinal slots in order to reach the tumblers is made possible and on the other hand it is impossible to detect the position of the tumblers by feeling them laterally by means of the coupling members of the pushers, taking advantage of any play which may exist between these coupling members and the combination members.

Another object of the invention is to provide a lock constructed so that whatever may be the position of a pusher, the inside of the revoluble cylinder affords no break in continuity between the keyhole opening of the lock and said lateral projection of the pusher.

For this purpose said pushers are formed by U-shaped pieces the branches of which are joined by said lateral projections guided in said longitudinal slots. One branch, namely the internal branch, is guided in a longitudinal keyway axially provided in said revoluble cylinder and the other

2

branch, namely the external branch, is guided on the outside of said cylinder. The latter branch carries at its ends the coupling members between which a tumbler places itself when it is coupled to the pusher.

Another object of the invention is to provide a lock having U-shaped pushers the internal branches of which are of such a length that the free ends thereof facing the keyhole opening of the lock always block said keyway, thus creating an obstruction to the passage of a tool towards said longitudinal slots of the revoluble cylinder.

Another object of the invention is to provide a lock having U-shaped pushers the external branches of which are of such a length that said external branches of the pushers when depressed form obstructions barring access from said longitudinal slots of said revoluble cylinder to said tumblers. In this manner said U-shaped pushers when depressed always close from outside and from inside the portion of said longitudinal slots which extend between the fore end thereof and said lateral projections joining the two branches of each pusher, whereby any passage from the keyway of the lock to the tumblers is prevented.

Another object of the invention is to provide a lock having U-shaped pushers the internal branches of which accommodated side by side in a central axial keyway of the lock have each a transverse section such that, when juxtaposed, they form together a body which entirely fills the above-mentioned axial keyway.

Another object of the invention is to prevent advantage being taken of any play which may exist between the coupling members and the tumblers, by sliding the pushers along the tumblers and causing them to bear laterally against the latter, whereby the position of the tumblers, and thus the combination employed to lock the lock might be ascertained. For this purpose said tumblers are, according to the invention, provided on their lateral longitudinal flanks with grooves the width of which corresponds to that of the coupling members of the pushers. The position, the spacing and if desired also the number of these grooves may be different on the two lateral flanks of each tumbler. These grooves on the one hand obscure the indications obtained by feeling the tumblers with the coupling members of the pushers and on the other hand they allow the coupling members to engage with these grooves, arresting the pushers in positions which do not allow of verifying whether they corre-

3

spond to the combination with which the lock has been locked.

Other characteristics and advantages of the new lock will be clear from the following description taken in conjunction with the accompanying drawing, which represents, merely by way of example, one form of construction of a lock in accordance with the invention.

In the drawing:

Figure 1 is a longitudinal section through the new lock on the line I—I of Figure 2, the parts being shown in the neutral position, for the sake of clarity only one pusher and one tumbler are illustrated.

Figure 2 is a transverse section on the line II—II of Figure 1.

Figure 3 is a section similar to that of Figure 2 but on the line III—III of Figure 1.

Figure 4 shows a longitudinal section of the lock in an axial plane passing through two pushers which have been moved back by the bits of the key which are of different length and which are disconnected from the tumblers by rotation of the internal cylinder.

Figure 5 is a perspective view of a tumbler coupled with its pusher.

The same reference numerals denote the same parts in the various figures of the drawing.

The cylindrical combination lock represented in the drawing comprises essentially a fixed external cylinder 1, a revolvable internal cylinder 2, movable pushers 3 which are guided longitudinally in the internal cylinder 2 and are displaceable against the action of the springs 4 by the bits 5 of adjustable length (Figure 4) of a key, and tumblers 6 which are displaceable in longitudinal grooves 7 of the fixed external cylinder 1. The above-mentioned pushers 3 are adapted to be coupled by a rotation of the cylinder 2 to the tumblers 6 in order to bring each of them into a position dependent upon the length of the bit which has displaced the corresponding pusher.

To this end said pushers are provided with coupling members protruding on the outside of the revolvable cylinder 2 across longitudinal slots 19 cut out in said cylinder. These slots are opened towards the end of the inner cylinder remote from the keyhole opening thereof and extend towards the fore end of the said cylinder over a distance which is necessary to allow the pushers to be moved from one extreme position to the other in the lock.

A rotation in the one direction or the other which is then imparted to the internal cylinder 2 releases the pushers 3 from the tumblers 6 which remain blocked in the position into which they have been carried, while the pushers 3 return under the action of their springs 4 towards the keyhole opening of the lock 8 when the key is withdrawn and dispose themselves between the tumblers and prevent any rotation of the cylinder 2.

In order to prevent detection of the combination with which the lock has been locked by feeling the tumblers by means of a tool being introduced through the keyhole opening 8 of the lock, all the pushers are accommodated in a single keyway 9 which is axially provided in said revolvable cylinder and the individual pushers are so shaped that, when placed one beside another, they fit together and form a polygonal prism which fills the keyway 9 entirely. In the example illustrated in the drawing the lock comprises six pushers each of triangular section and forming together a hexagonal prism which fits the section of the keyway 9. Furthermore, the pushers

4

3 are of a length such that even when they are pushed into their most advanced position (Fig. 4) their front ends 10 are still lying inside the uninterrupted portion of the keyway 9 adjacent to the keyhole opening and block the bottom end of it, so that the tumblers 6 and their guide grooves 7 in the external cylinder are inaccessible from the outside of the lock.

In order still further to increase safety of the lock, each pusher 3 forms part of a U-piece and of which it forms the internal branch which is disposed in the keyway 9 and is joined by a bridge piece 11 to a longitudinal member 12 which forms the external branch of said U-shaped piece. This external branch 12 is adapted to slide on the external face of the cylinder 2 and carries coupling noses 13—13' adapted to coact with the tumblers 6.

These coupling noses 13—13' are arranged at 20 the ends of the branches 12 of the pushers and the tumblers 6 are of a length such that, in the coupling position (Figs. 1 and 5) they are disposed between the noses 13—13'.

The bridge piece 11 is adapted to move in the 25 slot 19 of the cylinder 2.

The springs 4 acting on the U-shaped pushers are positioned in said slots 19 and bear against the bridge pieces 11.

The external branches 12 of the pushers 3 are 30 also of a length which is such that their front ends, namely the noses 13, are always applied on the external face of the cylinder 2 beyond the closed end of said longitudinal slots 19 (Figure 4). In this way the path which a tool has to take 35 from the keyhole opening 8 of the lock to a groove 7 is furthermore of winding form and would render impossible the passage of such tool. The branches 12 are accommodated entirely in grooves 14 of the internal cylinder 2 in such a 40 manner that only their noses 13—13' are outside the cylinder. In this manner, when the internal cylinder 2 is blocked and an attempt is made to turn it, the torsion is transmitted from the internal cylinder 2 directly to the noses 13 and 13' 45 over the whole length of the branches 12 of the pushers. This has the advantage that the bridge pieces 11 are not stressed at all and can consequently be relatively weak and need not necessarily be guided by the slot 19. Also the branches 50 12 always remain parallel to the axis of the lock.

These branches 12 and also their guide grooves 14 are advantageously of dovetail form (Fig. 5) which renders the accuracy of the working of the branches 12 independent of the guiding of the 55 pushers 3 and prevents them moreover from separating radially and engaging with the external cylinder.

The external branches 12 of the pushers have 60 a width which is equal or substantially equal to that of the tumblers 6 (Figure 5). The latter, and therefore also their guide grooves 7 in the external cylinder 1 are of dovetail form which prevents them from sliding radially out of the external cylinder.

65 In order to block the tumblers 6 in the position into which they have been moved by the pushers on the insertion of the key, the periphery of the internal cylinder 2 is provided between each pair of adjacent grooves 14 with a series of 70 projections or teeth 15 (Fig. 1) which, in the lock illustrated, have the form of segments of a circle (Fig. 2) and which engage in the teeth 16 provided on each movable tumbler 6 when the cylinder 2 is rotated. The projections 15 all 75 most entirely fill the space between two branches

12 of the pushers so that even a slight rotation of the cylinder 2 (Fig. 2) fixes the tumblers 6 in their position at the moment.

The end of the revoluble cylinder 2 is attached by suitable means to a bolt or the like to be actuated by the cylinder lock.

It has been found that it is possible to detect by touch the point where the coupling noses of the pushers reach the ends of the tumblers 6 by sliding these noses 13 and 13' along the combination members and pressing them against the flanks of the latter taking advantage of any play which allows of a slight rotation of the cylinder 2.

In order to prevent the discovery of the combination with which the lock has been locked by detecting in the manner described the position of the tumblers 6, in accordance with the invention, said tumblers are provided on their flanks with a plurality of grooves 18 arranged parallel to one another and having a width corresponding to that of the coupling noses 13—13'. The position and the number of these grooves and also the distance between two adjacent grooves may be different on the two flanks of the tumblers 6. The presence of the grooves 18 distributed asymmetrically in the flanks of these tumblers will baffle and mislead any person who endeavours to detect the combination of the lock by manipulating the pushers of the lock.

The rotating internal cylinder 2 may be displaced into three determined positions, namely two end positions in which the pushers 3 and the combination members 6 are angularly displaced relatively to one another, so that when the key is withdrawn the internal cylinder 2 is prevented from rotating, and a third position intermediate between the two above-mentioned end positions in which the pushers 3 and the tumblers 6 are coupled and from which position the internal cylinder 2 may be turned towards one or the other end position with any desired adjustment of the adjustable bits:

The lock according to the invention functions in the following manner.

When the lock has been brought into its neutral position (Figs. 1, 2 and 3) a key, the bits 5 of which have been adjusted according to a desired combination is introduced into the keyway 9. Each pusher and at the same time the tumbler 6 which being lodged between the noses 13 and 13' of the external branch 12 is thereby coupled to this pusher are moved together by an amount corresponding to the length of the bit which actuates the pusher in question. The amount of this displacement may if desired be different for each tumbler (Fig. 4). During the subsequent rotation of the key, and therefore of the internal cylinder 2, towards the one or the other of its two end positions, the noses 13 and 13' disengage the tumblers 6, and at the same time the segments 15 of the internal cylinder 2 engage in the teeth 16 of the tumblers 6 and fix the latter in the position into which they have been brought by the pushers 3.

During the removal of the key, the pushers 3 all return into their initial position under the action of their springs 4, so that their noses 13 and 13' take position between the tumblers 6. The latter thus prevent any angular displacement of the pushers 3 and accordingly of the internal cylinder.

From this position the cylinder can be brought into the intermediate neutral position or beyond the latter into the opposite end position only if

the key employed for this operation possesses the same setting of the bits as the key which had previously been used for bringing the lock from its intermediate neutral position into the first end position. If a key with a different adjustment is introduced and an attempt be made to rotate the internal cylinder 2 by means of that key, the noses 13 and 13' of the pushers 3 and the tumblers 6 remain displaced relatively to one another in the axial direction of the lock and prevent any rotation of the cylinder 2.

The three above-mentioned positions of the internal cylinder 2 may be intended in practice for the operation of a closing device, for example, the two end positions being employed to allow of unlocking and locking this device and the intermediary neutral position for altering the combination of the lock.

Having now particularly described and ascertained the nature of my invention and in what manner the same is to be performed, I declare that what I claim is:

1. A cylindrical combination lock to be locked by a combination key having longitudinally adjustable bits and to be unlocked only by a key of identical combination of bits comprising in combination two cylinders arranged concentrically one inside the other, the outer cylinder being fixed, the inner cylinder being rotatably mounted and provided axially with a longitudinally extending keyway opened towards the keyhole of the lock, pushers slidably accommodated side by side in said longitudinal keyway and depressed by the bits of the key when inserted in said keyway, springs actuating said pushers so as to impell them towards the keyhole opening of the lock, parallel longitudinal slots cut out in said rotatable cylinder, said slots being opened at the end of said cylinder remote from the keyhole of the lock and having a length less than the length of said cylinder, radial projections laterally provided on said pushers and protruding outwardly of said rotatable cylinder across said longitudinal slots, grooves longitudinally provided in said fixed cylinder, tumblers slidably arranged in said grooves, coupling means provided on said lateral projections for connecting said pushers and tumblers for a common longitudinal movement, whereby said tumblers are moved by action of said coupling means into positions corresponding to the combination biting selected, means for disconnecting said pushers from said tumblers when in said positions, means for locking said rotatable cylinder against rotation by cooperation of said pushers and tumblers, means for locking said tumblers from movement when disconnected from said pushers and means for preventing the position of said tumblers when locked from being detected by aid of means inserted from inside of said rotatable cylinder into the longitudinal slots thereof when the pushers are depressed.

2. A cylindrical combination lock to be locked by a combination key having longitudinally adjustable bits and to be unlocked only by a key of identical combination of bits comprising in combination two cylinders arranged concentrically one inside the other, the outer cylinder being fixed, the inner cylinder being rotatably mounted and provided axially with a longitudinally extending keyway opened towards the keyhole opening of the lock, pushers slidably accommodated side by side in said longitudinal keyway and depressed by the bits of the key when inserted in said keyway, springs actuating said pushers so as to im-

pell them towards the keyhole opening of the lock, parallel longitudinal slots cut out in said rotatable cylinder, said slots being opened at the end of said cylinder remote from the keyhole opening thereof and having a length less than the length of said cylinder, radial projections laterally provided on said pushers and protruding outwardly of said rotatable cylinder across said longitudinal slots, grooves longitudinally provided in said fixed cylinder, tumblers slidably arranged in said grooves, coupling means provided on said lateral projections for connecting said pushers and tumblers for a common longitudinal movement, whereby said tumblers are moved by action of said coupling means into positions corresponding to the combination bitting selected, means for disconnecting said pushers from said tumblers when in said positions, means for locking said rotatable cylinder against rotation by cooperation of said pushers and said tumblers, means for locking said tumblers when disconnected from said pushers and means for screening on both their sides said longitudinal slots between the closed ends thereof and said radial projections of said pushers when depressed.

3. A cylindrical combination lock to be locked by a combination key having longitudinally adjustable bits and to be unlocked only by a key of identical combination of bits comprising in combination an outer cylinder, an inner cylinder concentrically positioned in said outer cylinder, said outer cylinder being fixed, said inner cylinder being rotatably mounted with respect to said outer cylinder and provided axially with a longitudinally extending keyway opened towards the keyhole opening of the lock, pushers slidably accommodated side by side in said longitudinal keyway and movably depressed by the bits of a key when inserted in said keyway, springs actuating said pushers so as to impell them towards the keyhole opening of the lock, parallel longitudinal slots cut out in said rotatable cylinder, said slots being opened at the end of said cylinder remote to the keyhole opening and having a length less than the length of said cylinder, radial projections laterally provided on said pushers and protruding outwardly of said rotatable cylinder across said longitudinal slots, grooves longitudinally provided in said outer cylinder, tumblers slidably arranged in said longitudinal grooves of said outer cylinder, coupling means for connecting said pushers and tumblers for a common longitudinal movement, whereby said tumblers are moved by action of said coupling means into positions corresponding to the combination bitting selected, means for disconnecting said pushers from said tumblers when in said positions, means for locking said rotatable cylinder against rotation by cooperation of said pushers and said tumblers, means for locking said tumblers when disconnected from said pushers, a longitudinally extending member provided on said radial projection of each pusher and slidably guided in the direction of said longitudinal slots on the outside of said rotatable cylinder, whereby U-shaped tumbler actuators are formed with parallel branches joined by said radial projections and having their free ends directed towards the keyhole opening end of said rotatable cylinder, said U-shaped tumbler actuators being of such a length and width, that when depressed they overlap on both their sides said longitudinal slots between the closed ends thereof and said lateral projections of said pushers, said coupling means being carried by the branches of said U-shaped tumbler actuators extending on the outside of said rotatable cylinder.

4. A cylindrical combination lock to be locked by a combination key having longitudinally ad-

justable bits and to be unlocked only by a key of identical combination of bits comprising in combination an outer cylinder, an inner cylinder concentrically positioned in said outer cylinder, said outer cylinder being fixed, said inner cylinder being rotatably mounted with respect to said outer cylinder and provided axially with a longitudinally extending keyway opened towards the keyhole opening of the lock, pushers slidably accommodated side by side in said longitudinal keyway and movably depressed by the bits of a key, when inserted in said keyway, springs actuating said pushers so as to impel them towards the keyhole opening of the lock, parallel longitudinal slots cut out in said rotatable cylinder, said slots being opened at the end of said cylinder remote to the keyhole and having a length less than the length of said cylinder, a radial projection laterally provided on the end of said pushers remote to the keyhole opening of the lock and protruding outwardly of said rotatable cylinder across a longitudinal slot thereof, grooves longitudinally provided in said outer cylinder, tumblers slidably arranged in said longitudinal grooves of said outer cylinder, coupling means for connecting said radial projections and tumblers for a common longitudinal movement, whereby said tumblers are moved by action of said coupling means into positions corresponding to the combination bitting selected, means for disconnecting said coupling means from said tumblers when in said positions, means for locking said rotatable cylinder against rotation by cooperation of said coupling means and said tumblers, means for locking said tumblers when disconnected from said pushers, a longitudinally extending member provided on said radial projection of each pusher and slidably guided in the direction of said longitudinal slots on the outside of said rotatable cylinder, whereby U-shaped tumbler actuators are formed with parallel branches joined by said radial projections and having their free ends directed towards the keyhole opening end of said rotatable cylinder, said U-shaped tumbler actuators being of such a length and width, that when depressed they overlap on both their sides said longitudinal slots between the closed ends thereof and said lateral projections of said pushers, said coupling means being carried by the branches of said U-shaped tumbler actuators extending on the outside of said rotatable cylinder.

5. A cylindrical combination lock to be locked by a combination key having longitudinally adjustable bits and to be unlocked only by a key of identical combination of bits comprising in combination an outer cylinder, an inner cylinder concentrically positioned in said outer cylinder, said outer cylinder being fixed, said inner cylinder being rotatably mounted with respect to said outer cylinder and provided axially with a longitudinally extending keyway opened towards the keyhole of the lock, pushers slidably accommodated side by side in said longitudinal keyway and movably depressed by the bits of a key when inserted in said keyway, said pushers having a cross section so shaped that when juxtaposed they completely fill said keyway, springs actuating said pushers so as to impel them towards the keyhole opening of the lock, parallel longitudinal slots cut out in said rotatable cylinder, said slots being opened at the end of said cylinder remote to the keyhole opening and having a length less than the length of said cylinder, a radial projection laterally provided on the end of said pushers remote to the keyhole opening of the lock and protruding

outwardly of said rotatable cylinder across a longitudinal slot thereof, a longitudinally extending member provided on said radial projection of each pusher and slidably guided in the direction of said longitudinal slot on the outside of said rotatable cylinder, whereby U-shaped actuators are formed with parallel branches joined by said radial projections and having their free ends directed towards the keyhole opening end of said rotatable cylinder, said U-shaped actuators being of such a length and width that when depressed they overlap on both their sides said longitudinal slots between the closed ends thereof and said lateral projections of said pushers, grooves longitudinally provided in said outer cylinder, tumblers slidably arranged in said longitudinal grooves of said outer cylinder, coupling means provided on the said U-shaped actuators' branches extending on the outside of said rotatable cylinder for connecting said actuators and tumblers for a common longitudinal movement, whereby said tumblers are moved by action of said coupling means into positions corresponding to the combination bitting selected and for disconnecting said coupling means from said tumblers when in said positions by a rotation of said rotatable cylinder, means for locking said rotatable cylinder against rotation by cooperation of said coupling means and said tumblers, means for locking said tumblers when disconnected from said U-shaped actuators, said coupling means consisting of noses radially provided at opposite ends of said U-shaped actuators' external branches and separated by a distance equal to the length of said tumblers, so that said tumblers when connected to said U-shaped actuators are engaged between said coupling means.

6. A cylindrical combination lock to be locked by a combination key having longitudinally adjustable bits and to be unlocked only by a key of identical combination of bits comprising in combination an outer cylinder, an inner cylinder concentrically positioned in said outer cylinder, said outer cylinder being fixed, said inner cylinder being rotatably mounted with respect to said outer cylinder, and provided axially with a longitudinally extending keyway opened towards the keyhole of the lock, tumblers slidably arranged in longitudinal grooves provided in said outer cylinder, parallel longitudinal slots cut out in said rotatable cylinder, said slots being opened towards the end thereof remote from the keyhole and having a length less than the length of said cylinder, U-shaped tumbler actuators slidably arranged in said rotatable cylinder and movably depressed by the bits of a key when inserted in said keyway, said U-shaped actuators having their free ends directed towards the keyhole opening end of said cylinder, said U-shaped tumbler actuators having each an internal branch and an external branch joined by a cross-piece movable in a longitudinal slot of said cylinder, the internal branches of said U-shaped actuators being slidably accommodated side by side in said keyway and having each a cross section so shaped that when juxtaposed, they completely fill said keyway, the external branches of said U-shaped tumbler actuators being slidably guided in the direction of said longitudinal slots on the outside of said rotatable cylinder, said inner and external branches of said U-shaped tumbler actuators being of such a length that when depressed, they overlap on both their sides said longitudinal slots between the closed ends thereof and said cross pieces of said tumbler actuators, coupling means provided

on said external branches for connecting said actuators and tumblers for a common longitudinal movement, whereby said tumblers are moved by action of said U-shaped actuators into positions corresponding to the combination bitting selected and for disconnecting said actuators from said tumblers when in said positions, means for locking said rotatable cylinder against rotation by cooperation of said coupling means and said tumblers, means for locking said tumblers when disconnected from said U-shaped actuators and springs positioned within said longitudinal slots of said rotatable cylinder, so as to bear on said cross pieces of said U-shaped tumbler actuators between both branches thereof.

7. A cylindrical combination lock to be locked by a combination key having longitudinally adjustable bits and to be unlocked only by a key of identical combination of bits comprising in combination an outer cylinder, an inner cylinder concentrically positioned in said outer cylinder, said outer cylinder being fixed, said inner cylinder being rotatably mounted with respect to said outer cylinder and provided axially with a longitudinally extending keyway opened towards the keyhole of the lock, tumblers slidably arranged in longitudinal grooves provided in said outer cylinder, parallel longitudinal slots cut out in said rotatable cylinder, said slots being opened towards the end thereof remote from the keyhole and having a length less than the length of said cylinder, U-shaped tumbler actuators slidably arranged in said rotatable cylinder and movably depressed by the bits of a key, when inserted in said keyway, said U-shaped actuators having their free ends directed towards the keyhole opening end of said cylinder, said U-shaped tumbler actuators having each an internal branch and an external branch joined by a cross-piece movable in a longitudinal slot of said cylinder, springs positioned within said longitudinal slots of said rotatable cylinder, so as to bear on said cross pieces of said U-shaped tumbler actuators between both branches thereof, whereby said tumbler actuators are impelled towards the keyhole opening end of said inner cylinder, the internal branches of said U-shaped actuators being slidably accommodated side by side in said keyway and having each a cross section so shaped that when juxtaposed, they completely fill said keyway, the external branches of said U-shaped tumbler actuators extending parallel to said internal branches in the direction of said longitudinal slots on the outside of said rotatable cylinder, said inner and external branches of said U-shaped actuators being of such a length and width that when depressed, they overlap on both their said longitudinal slots between the closed ends thereof and said cross pieces of said tumbler actuators, coupling means provided on said external branches for connecting said actuators and said tumblers for a common longitudinal movement, whereby said tumblers are moved by action of said U-shaped actuators into positions corresponding to the combination bitting selected, and for disconnecting said actuators from said tumblers when in said positions, means for locking said rotatable cylinder against rotation by cooperation of said coupling means and said tumblers, means for locking said tumblers when disconnected from said U-shaped actuators and longitudinal dovetailed grooves provided on the outside of said rotatable cylinder for slidably guiding said external branches of said U-shaped tumbler actuators, said grooves having the depth equal to the thickness of said external branches, so that

only said coupling means are projecting out of said inner cylinder.

8. A cylindrical combination lock to be locked by a combination key having longitudinally adjustable bits and to be unlocked only by a key of identical combination of bits comprising in combination an outer cylinder having longitudinal grooves, an inner cylinder concentrically positioned in said outer cylinder having peripheral longitudinal grooves and, said outer cylinder being fixed, said inner cylinder being rotatably mounted with respect to said outer cylinder and provided axially with a longitudinally extending keyway opened towards the keyhole of the lock, tumblers slidably arranged in said longitudinal grooves provided in said outer cylinder, parallel longitudinal slots cut out in said rotatable cylinder, spring pressed U-shaped tumbler actuators slidably arranged in said rotatable cylinder and movably depressed by the bits of a key, when inserted in said keyway against the spring action, said U-shaped tumbler actuators having each an internal branch and an external branch joined by a cross-piece movable in a longitudinal slot of said cylinder, the internal branches of said U-shaped actuators being slidably accommodated side by side in said keyway and having each a cross section so shaped that when juxtaposed, they completely fill said keyway, the external branches of said U-shaped tumbler actuators extending parallel to said internal branches in the direction of said longitudinal slots and slidably guided on the outside in said peripheral longitudinal grooves provided in said rotatable cylinder, said inner and external

branches of said U-shaped tumbler actuators being of such a length and width that when depressed, they overlap on both their sides said longitudinal slots between the closed ends thereof and said cross pieces of said tumbler actuators, coupling noses provided on said external branches and adapted to receive said tumblers between them for connecting said actuators and said tumblers for a common longitudinal movement, whereby said tumblers are moved by action of said U-shaped actuators into positions corresponding to the combination biting selected and for disconnecting said actuators from said tumblers when in said positions, means for locking said rotatable cylinder against rotation by cooperation of said coupling noses and said tumblers, means for locking said tumblers when disconnected from said coupling noses and notches provided on tumblers flanks constacting said longitudinal grooves in said outer cylinder, said notches extending parallel to said coupling noses of said U-shaped actuators and having the same width as said noses.
